UNITED STATES PATENT OFFICE

MORRIS KOPPELMAN, OF BROOKLYN, NEW YORK

PACKING HOLDER FOR FRAGILE ARTICLES

Application filed August 8, 1930. Serial No. 473,965.

The present improvements relate to packing for fragile articles of the general type described and claimed in my Patent No. 1,746,838 of February 11, 1930 and in the co-pending application of Gray, et al., Serial No. 427,116 filed February 10, 1930, upon which the present invention is an improvement.

A primary object, among others, is to provide a foldable holder of the general type indicated wherein the fragile articles, such as eggs, fruits and other globular articles, which are packed therein, are protected against crushing or breakage from above and below.

A further object of the improvements is to provide a more substantial and durable holder which is capable of absorbing and resisting shocks tending to impair the contents. Improved cushion means as well as novel foldable means are therefore provided contributing various advantages and results.

Another object is to provide an improved holder for use as a container itself without any wrapper, or as a holder or filler within other cartons or containers.

Further objects and advantages of the improvements will be apparent to those skilled in the art upon reference to the accompanying specification and drawings in which

Fig. 1 is a plan view of a portion of the improved holder in unfolded position;

Fig. 2 is a section on line 2—2 of Fig. 1;

Fig. 3 is a section on line 3—3 of Fig. 4;

Fig. 4 is an enlarged top plan view of the holder in folded position;

Fig. 5 is a section on line 5—5 of Fig. 4;

Figs. 6 and 7 are plan and sectional views respectively of a portion of a modified form.

Reference may be had to my aforementioned patent for details of the general type of holder or filler described herein and also for the methods employed in forming this one piece member.

In the embodiments illustrated herein, the carton or filler also consists of a single sheet of material, all parts of which are preferably formed integral with the sheet in one operation. The sheet is preferably formed by the pulp sucking or felting process where-

in floating fibres are drawn against a screen member, so that the carton or filler is created complete in one operation. Accordingly, the foraminous die or mold is so shaped that the pulp deposited thereon will assume the prescribed form and contour of the filler.

In the present embodiment, a portion only of sheet 10 is illustrated for convenience. Said sheet comprises a plurality of substantially parallel sections or wall portions 11 to 14. Each wall portion includes a series of alternately disposed projections 15, 15^a, 16, 16^a, and depressions 20 merging with one another and with the edges of the portions, so as to present a wall member of continuously curved or arched surfaces. Although any desired number of the elements may be provided to comprise the walls, I preferably provide seven projections and six depressions in each wall in the manner observed in my patent. The sheet 10, thus arranged, is capable of receiving a dozen individual articles as will appear later.

The projections aforementioned define separators or partitions for individual articles and are of substantially pyramidal or prismatic form, the walls thereof being curved or cambered toward the depressions with which they merge. As illustrated these projections or protuberances substantially traverse the wall portions of which they form an integral part. Referring to elements 15 and 16, it is seen that they protrude to their greatest extent substantially medially of the wall portion, at which region, their outermost portions are narrow in the nature of a ridge. However these formations are broader adjacent the edges of the wall portions, for example at 17 where they curve or camber toward the upper folding means, and at 18 where they extend to meet the lower folding means, curving away in opposite directions where they merge with the lower curved portions of the depressions.

The separators or partitions 15^a and 16^a on the outer side walls 11 and 12 respectively are similar in many respects to their complementary elements 15 and 16, except that the cambered end portions 17 are dispensed with and the elements retain their protruding

form to the edges of the walls. It is apparent that the upper portions of elements 15^a and 16^a curve away from the ridges, the latter however extending to the edges of the walls so that they define indentations of the curved or scalloped edges 19 as clearly seen in Fig. 4. A comparison of elements 15, 15^a, 16, 16^a may be clearly observed in Fig. 3, where the folded condition of the holder is illustrated.

The depressions 20 are cup-like recesses integral with the sheet and disposed between adjacent projections. In the present embodiment these depressions are concave and are substantially oval shaped. While these depressions extend in a direction opposite to that of the projections, it is notable that the curved walls of the depressions merge with their flanking projections, so that a half-ovoid cavity results.

It will be observed that the depressions 20 and projections 15, 16 are similar to those of my patent, wherein these elements on one wall member are disposed opposite to those of the adjacent wall member, so that similar members on adjacent wall members are complementary.

Adjacent or complementary wall members 11, 13 and 12, 14 are united by an integral folding means 22 defining a hinge whereby the walls may be folded towards each other. This folding means has been illustrated in enlarged views (Figs. 3 and 5) where their relation has been slightly exaggerated for convenience in explanation. The folding means 22 form, with the converging lower curved surfaces of recesses 20 and portions 18 of the projections, a minute U-shaped channel (Fig. 2). When folded this channel is more pronounced at some points as seen in Fig. 3, than at others as seen in Fig. 5.

As set forth in my prior patent, the lower curved surfaces of the depressions 20 converge toward the folding means 22 and merge therewith slightly above the lowermost limits of said means.

Referring to Fig. 1, it is seen that depressions or ribs 23 intersect hinge means 22, said members being bulged from the curved surfaces of the depressions and extending toward the member 22.

The lower curved surfaces of recesses 20 are provided with cushion means of any desired form or quantity. Preferably they consist of portions raised or bulged from the surface of the recess as seen at 25. It is thus seen that when the holder is folded, these cushions 25 cooperate to provide a cushion base upon which an individual article may rest and thus have its lower portion slightly raised above the lower limit of the holder which is defined by the bottom of folding means 22. It is notable that the cushioned areas 25 may be provided by the intersection of members 22 and 23, since they

protrude from the lower surfaces of depressions 20. The provision of the cushions in this manner may be preferable, although either method provides raised formations at the base of the ovoidal cavity.

As illustrated, the inner wall members 13 and 14 are united by an upstanding folding means or central hinge 30. This element is similar in structure and function to the central hinge member illustrated in the aforementioned copending application of Gray, et al. As seen in Fig. 1, the ribs 23 extend into the folding means 30, the latter also being provided with additional reinforcement such as ribs 31. This construction provides an unusually rigid and shock resisting hinge means and functions to receive, absorb and dissipate shocks, thereby protecting the packed articles.

Upon reference to Figures 3, 4 and 5, sheet 10 is seen in folded relation to form an article holder. Through this simple folding operation the inner walls 13 and 14 are brought substantially back to back, while their complementary outer walls 11 and 12 are also disposed in upstanding relation with the complementary projections and depressions of each of the four walls brought into juxtaposition, the projections substantially meeting along their medial or lower limits. Accordingly, the depressions 20 together with the separators or partitions 15, 15^a, 16, 16^a, provide a plurality of individual cells or compartments, each having a cushion base provided by members 25. The curved and merging walls of the partitions and depressions provide rounded or ovoid shaped cells which conform to the contour of an egg which is adapted to seat on the cushioned members. The contraction or convergence of the lower surfaces of the depressions, insures that the lower walls of the completed compartment will conform to the contour of an egg. However, it is apparent that the shape of the article conforming depressions may be varied to suit the contour of other articles. In packed condition the articles are inclosed and supported by the holder, are completely separated one from the other, and are efficiently cushioned and protected due to the form and texture of the holder and its various elements.

In addition to advantages already noted, the present improvements provide individual cushioning means for the packed articles without sacrificing the advantages of my patented structure. When the articles are packed in the holder, as for example in a surrounding carton 35 (see Fig. 3) it is important that they be protected from shocks from above as well as from all directions, and accordingly the present improvements provide the upstanding central connecting portion 30 as well as the outer scalloped edges 19 having the inwardly protecting portions

36, all of which extend vertically above the level of the eggs for receiving the shocks or pressure which otherwise might be experienced by the tips of the eggs themselves.

5 Although the upstanding central hinged portion 30 serves to protect the contents of the holder from shocks received along the central portion of the carton or wrapper 35, heretofore no provision has been made for 10 the protection of the articles from shocks sustained between the center and outer edges of the carton, that is, shocks received directly over the rows of eggs. Accordingly the top of the carton 35 bulged inwardly until 15 the tops of the eggs were encountered whence the shocks were transferred directly to the eggs with the possible breakage thereof. However, by extending the separators or partitions 15^a, 16^a vertically to the point 36 so 20 that they are substantially flush with the member 30, the shortcomings of prior devices have been eliminated. As aforementioned, the upper edges of these partitions provide a scalloped edge with the points 36 providing 25 a series of pressure resisting elements which prevent the top of the carton from bulging inwardly under pressure, thereby protecting the rows of eggs at points in alignment with their upper ends, and between the outer and 30 central portions of the holder.

This refinement of construction cannot be overemphasized in a W-shaped filler of this character, wherein the upper areas of the V-shaped component must necessarily expose 35 the articles. By attaining this desired result in a one-piece filler, the advantages of my patented construction both as regards function and convenience in manufacture, have not been sacrificed.

40 It is manifest upon reference to Figure 3 and others that the substantially U-shaped folding means 22 itself provides a longitudinal cushion means along the bottom of each row beneath the packed articles. This arrangement likewise presents a relatively flat 45 surface in the nature of a base. Furthermore, the fact that the members 22 having a slight width, the projecting partitions are enabled to approach and contact thereover, 50 which might not be the case where a single fold line is provided. It is possible in this construction last referred to, that an excess of pulp fibres might be deposited in such a 55 manner as to prevent meeting of the partitions along the desired areas.

In addition to the assurance that the partitions may engage, it is seen that the U-shaped hinge means provides an air duct longitudinally of each row along the bottoms thereof. Furthermore, the provision of this type of folding means is unusually advantageous 60 since the region where the actual bending or folding takes place is not limited to a single line but, when made, may follow its own 65

course along the channel rather than along a definite prescribed line.

With further reference to the members 23, which are bulged from the upstanding walls of the holder, it is notable that they serve as 70 buffers or spacers, and therefore prevent the articles as well as the article compartments of one cell row from contacting or engaging those of the adjacent cell row. Accordingly the curved depressions 20 are spaced one from 75 another, even though the ribs 23 are engaging, and the said wall members are in upright article holding position. It is notable also that the upper portions of ribs 23 as well as the shorter ribs 31 stiffen the cup-shaped recesses and also the connecting portion 30. 80

The holder of the modified form illustrated in Figures 6 and 7 is substantially the same as that of the form first described, except that the separators or partitions 15^a and 16^a are 85 omitted, the elements substituted therefor being similar to the partitions 15 and 16 of the inner upstanding walls 13 and 14. As set forth in my patented structure, it is apparent that the upstanding walls, cup-shaped 90 depressions and engaging partitions, serve as cushions or spacers for cushioning and resisting shocks laterally, vertically, and obliquely of the holder.

Various modifications of the improvements 95 may occur to those skilled in the art and may be made without departing from the purview of the invention.

I claim:

1. A foldable holder having side wall 100 members united by folding means defining a double hinge therefor, complementary depressions in said members having surfaces converging toward said means, one of said surfaces terminating above the lowermost 105 limit of said folding means.

2. A foldable holder having side wall 110 members united by folding means defining a double hinge therefor, complementary depressions in said members having surfaces 115 converging toward said means, one of said surfaces terminating above the lowermost limit of said folding means and a portion depressed from said last named surface, said portion extending toward the lowermost limit 120 of said folding means.

3. An article of manufacture comprising a sheet of material having folding means for folding same into a plurality of inclined walls defining substantially V-shaped rows, 125 said walls comprising a continuous series of depressions and projections merging with one another and extending toward the lower limits of said rows, said folding means forming a U-shaped area with the lower limits of 130 the rows and providing bases for the several rows.

4. A holder for fragile articles comprising a sheet of material created with a series of rows of depressions and projections therein, 135

- integral double-line hinge means protruding between each of said rows whereby they may be folded toward one another with said hinges protruding, said rows when folded having complementary projections substantially contacting above said protruding hinges.
5. In a foldable holder, an upstanding wall having a hinge portion, said wall having a plurality of depressions and projections, said projections extending upwardly to the upper limit of the wall and defining the uppermost edge thereof, the vertical edges of said projections extending undeviatingly in a vertical plane and substantially aligned with said hinge portion and terminating above the limits of the articles received in said depressions, at points substantially in register with the axial planes of such articles.
- 10 6. In a foldable holder, an upstanding wall having a hinge portion, said wall having a plurality of depressions and bulged formations defining partitions, said partitions extending upwardly to and forming the upper edge of the wall the forward edges of said partitions being substantially vertical and the upper edges substantially horizontal.
- 15 7. A holder for fragile articles comprising a sheet of material having article holding portions and connecting portions, said sheet being foldable along said connecting portions to form a W-shaped holder and means defining the upper edges of said holder protruding horizontally and inwardly to a position substantially above said connecting portions and thence downwardly for protecting the contents thereof.
- 20 8. A foldable V-shaped receptacle having side walls connected by a hinge member, one of said walls having a bulged formation defining a partition extending, without receding, to the upper limit of the wall.
- 25 9. A foldable W-shaped receptacle having outer and inner side walls connected by hinge members, the outer walls having bulged formations defining partitions having upstanding edges extending substantially in a single plane to the upper limits of the walls, the hinge member between the said inner walls being substantially flush with the upper limits of the outer walls.
- 30 10. In a fragile article holder, a substantially V-shaped compartment the side walls of which have protruding article separators certain of said separators extending vertically to a greater extent than the others.
- 35 11. An upstanding foldable receptacle having side wall members and a hinge between same adjacent the base thereof, bulged formations protruding from said walls and forming separators between individual articles, said formations originating adjacent said hinge and extending upwardly therefrom, and terminating at unequal heights the upper edges of the higher formations being substantially horizontal.
- 40 12. An upstanding foldable receptacle having side wall members and a hinge between same adjacent the base thereof, a row of bulged formations protruding from each wall and forming separators between individual articles, said formations originating adjacent said hinge and extending upwardly therefrom, one row of formations being higher than the other row the upper edges of the formations of the higher row being substantially horizontal.
- 45 13. A foldable holder having wall members connected by hinge means, said wall members having protruding partition means registering with one another whereby upon folding the walls, said partition means provide article compartments, said hinge means comprising substantially parallel spaced hinge lines whereby adjacent edges of the wall members are spaced.
- 50 14. In a fragile article holder, a vertical member defining the wall of a row for packing fragile articles, a hinge member at the bottom of said wall for folding same, and bulged formations on said wall having their upper horizontal edges substantially at right angles to their erect edges.
